US0D1090467S

(12) **United States Design Patent** (10) **Patent No.:** **US D1,090,467 S**
(45) **Date of Patent:** **** Aug. 26, 2025**

(54) **BIPOLAR PLATE**

(71) Applicant: **North-West University**, Potchefstroom (ZA)

(72) Inventors: **Georgievich Dmitri Bessarabov**, Potchefstroom (ZA); **Stephanus Phillipus Oelofse**, Potchefstroom (ZA); **Ted Cornelis Paarlberg**, Potchefstroom (ZA); **Stephanus Petrus Du Preez**, Brits (ZA)

(73) Assignee: **North-West University**, Potchefstroom (ZA)

(**) Term: **15 Years**

(21) Appl. No.: **29/885,361**

(22) Filed: **Feb. 23, 2023**
